TEMPERATURE REGULATOR

William B. Mackintosh, Anderson, Ind., assignor,
by mesne assignments, to The Fulton Sylphon
Company, Knoxville, Tenn., a corporation of
Delaware

Application December 26, 1935, Serial No. 56,250

1 Claim. (Cl. 236—34)

This invention relates to temperature regulators, and more particularly to temperature regulators of the type employed for controlling the circulation of cooling water through the cooling systems of internal combustion engines, especially automobile engines.

It is an object of this invention to provide a temperature regulator of the type characterized which is of simplified and improved construction for controlling the flow of cooling medium through a cooling system of the by-pass type.

Another object of this invention is to provide an improved device of the type characterized wherein the main valve and the by-pass valve may be made of unitary construction.

Another object of this invention is to provide an improved device of the type characterized which may be inexpensively constructed of simple parts that are easily fabricated.

Another object of this invention is to provide an improved device of the type characterized that forms a self-contained unit which may be readily mounted in and demounted from operative position in the engine cooling system.

Another object of this invention is to provide an improved device of the type characterized which employs a valve member of tubular construction which by cooperation with the associated passages facilitates the building of the valve member and the maintenance of its movement in a rectilinear path.

Another object of this invention is to provide an improved device of the type characterized which employs a flanged tubular valve member having a closed end which operates as a by-pass valve member while the flange thereon operates as a main valve member.

Other objects will appear as the description of the invention proceeds.

The invention is capable of receiving a variety of mechanical expressions, some of which are illustrated on the accompanying drawing, but it is to be expressly understood that the drawing is for purposes of illustration only, and is not to be construed as a definition of the limits of the invention, reference being had to the appended claim for that purpose.

Referring in detail to the drawing, wherein the same reference characters are employed to designate corresponding parts in the several figures,

Fig. 1 is an elevation, partly in section, of an embodiment of the present invention;

Fig. 2 is an elevation of a regulator of a some-

what modified construction removed from its associated conduits; and

Fig. 3 is an axial cross section of another embodiment of this invention.

Referring in detail to the drawing, 10 designates a conduit member of any suitable size, construction and material and designed to form a part of the cooling system of an internal combustion engine. As illustrated, it takes the form of a casting adapted to be secured to the header of the engine in any suitable way, as by bolts 11 extending through apertures in the flange 12 of said casting, and provided with a passage 13 leading to the radiator, so that the regulator to be described may be mounted in suspended relation in the water of the header of the cooling water jacket. It is to be expressly understood, however, that the invention is not limited to an installation in this particular location, as if preferred the regulator to be described may be installed in any other suitable position in the cooling system. As shown, the casting 10 is provided with a by-pass conduit 14, illustrated as formed integrally with the casting 10, the wall of the by-pass conduit extending inwardly and then axially so as to provide a chamber 15 which communicates with the by-pass conduit proper through a port 16 and which has at its inner extremity an aperture 17 axially aligned with said port 16.

The regulator of the present invention is preferably formed as a self-contained unit composed of a combined valve seat and thermostat support, a thermostat mounted thereon, and a combined main and by-pass valve, preferably formed as a single member, suitably attached to the thermostat. As illustrated, an annular or otherwise suitably shaped plate-like element 18 is designed to be clamped in position between the casting 10 and the engine header and has centrally thereof a valve port 19. Mounted on said element 18 is a thermostat support 20, here shown as taking the form of a U-shaped strap which at its extremities is passed through apertures in the element 18 and suitably retained therein as by staking, upsetting, soldering, or otherwise. As shown in Fig. 1 said strap 20 may be of uniform width throughout, or as indicated in Figs. 2 and 3 said strap may be of reduced width at intermediate portions of the legs as indicated at 21.

Attached in any suitable way to the central portion of said strap 20 is a thermostat 22 of any suitable size, character and construction, but here shown as in the form of an expandable and collapsible deeply corrugated tubular metal chamber, charged in any suitable way with any suitable

thermosensitive fluid, that has its stationary end wall 23 suitably secured to the strap 20. The opposite and movable end 24 of said thermostat has attached thereto in any suitable way a stem 25 for transmitting the movements of said movable end wall to the valve member next to be described. As shown in Fig. 3, said stem 25 may be threaded at its outer extremity so that the valve member may be attached thereto by threading thereonto, after which it may be fixedly retained in the desired position by soldering, pinning or otherwise securing the valve member rigidly to said stem. In place of the attachment just described, however, the stem may be otherwise attached to the valve member as apparent from the other embodiments.

The combined main and by-pass valve member of the present invention is preferably formed as a single piece and, for facility of manufacture, it is preferably formed of sheet metal drawn to the desired shape. As illustrated said valve member is composed of a tubular portion 26 which has a closed end 27 and an outwardly extending flange 28 at its opposite extremity. While, if preferred, said flange may extend in a plane at right angles to the axis of the stem 25, it is preferably flared outwardly as shown in Fig. 3 so as to lie at an angle to the plane of the element 18, whereby it makes a line contact with the edge of said element 18 at the periphery of the port 19. In the construction shown in Fig. 3 the opposite end 27 of said valve member is bent inwardly so as to provide an interiorly threaded hub 29 which together with the extremity of the stem 25 completes the closed end of the valve member, but if preferred the valve member may be formed as a cup, with an imperforate closed end that is soldered or otherwise suitably secured to the end of the valve stem, as apparent from Fig. 2. The tubular portion 26 of said valve member is provided with one or more apertures 30 to permit the flow of liquid through said valve member as hereinafter explained.

Aperture 17 heretofore referred to is of such size as to have a free sliding fit with the periphery of the tubular portion 26 of said valve member, so that said valve member is guided in its movements by its coaction with said aperture 17, and said valve member is thereby restrained to rectilinear movement. The valve port 16 is of somewhat smaller size than the closed end of said valve member, so that when said valve member engages its closed end 27 with the wall of the chamber 15 containing said port 13 said port 16 is closed.

With the regulator mounted as illustrated in Fig. 1, the flange 28 of the valve member is in engagement with the element 18 and closes the port 19 when the thermostat 22 is contracted. The fluid medium flowing through the engine jacket flows through the interior of tubular valve portion 26 and through the ports 30 into the chamber 15, from which it flows through the port 16 into the by-pass 14. When the temperature of the cooling medium rises above that temperature at which the regulator is designed to initiate its movement, the thermostat 22 begins to expand as indicated in dotted lines in Fig. 2, and the flange 28 is moved away from the port 19, the closed end 27 of the valve member approaching the port 16, and thereby some of the cooling medium is permitted to flow through the port 19 and passage 13 to the radiator while the remainder of the flow is through the by-pass as just described. Thereby the flow of the cooling medium through the radi-

ator is proportioned to the temperature of the cooling medium. If the temperature of the cooling medium continues to rise thermostat 22 continues to expand until the closed end 27 of the valve member engages the wall of the chamber 15 and closes the port 16, at which time flange 28 is in its most remote position from the port 19. In this position no cooling medium can flow through the by-pass 14, but all of the flow is around the valve member through the port 19 and 10 through the passage 13 to the radiator.

By reason of the construction illustrated and described it will be perceived that the regulator of the present invention is composed of a minimum number of easily fabricated parts. The element 18 may be stamped from sheet metal; the thermostat support 20 may be stamped from sheet metal and bent into shape, and its ends may be secured to the element 18 by a simple operation; the valve member may be drawn from sheet metal and readily secured to the end of the valve stem which itself may be a simple piece of rod stock threaded or otherwise suitably formed at its ends; and the thermostat may be simply formed from deeply corrugated tubing, with one end integral therewith if preferred, and closed at its other end, or at both ends if preferred, by suitable disks attached to the end folds of the corrugated tubular wall in a manner well understood in the art. Therefore, all of the parts of the regulator may be simply formed by inexpensive manufacturing operations and the parts assembled at low cost. By use of a single tubular valve member closed at one end and flanged at the other end and cooperating with ports adapted to be respectively closed by said closed end and said flange, a particularly simple and efficient by-pass valve member has been provided. At the same time the device is easy to install, and in operation it functions to nicely proportion the flow of cooling medium between the radiator and the by-pass so as to maintain the desired cooling effect of the cooling medium.

While the embodiments of the invention illustrated on the drawings have been described with considerable particularity, it is to be expressly understood that the invention is not restricted thereto, as the same is capable of receiving a variety of mechanical expressions, some of which will now readily suggest themselves to those skilled in the art, while changes may be made in the details of construction, material, arrangement, proportion, etc., of parts without departing from the spirit of this invention. Reference is therefore to be had to the appended claims for a definition of the invention.

What is claimed is:

In a temperature regulator for controlling the flow of cooling medium through a by-pass type of internal combustion engine cooling system, said system including a by-pass port, a valve mechanism adapted to be installed in and removed from the cooling system as a unit, said unit including a member adapted to be installed as a partition across a passage of said cooling system on the up-stream side of the junction of the by-pass with the main passage of said system, said member being apertured to provide a valve port, a strap-like frame member carried by said first-named member and projecting therefrom, a bellows thermostat having one end secured to said strap-like frame member and its opposite end movable toward and away from said valve port, a valve stem projecting from the movable end of said thermostat through said valve port, and a

cup-shaped valve member on the opposite side of said first-named valve member from said thermostat and having the bottom wall of its cup secured to the end of said valve stem and adapted to close 5 said by-pass port, said cup-shaped valve member being apertured and adapted to operate as a by-pass valve to close and open respectively the by-pass as said cup-shaped valve member is moved away from and toward said first-named member 10 and said cup-shaped valve member having a flared

flange at the open mouth of its cup disposed at an angle to the plane of said partition member and adapted to make line contact with said valve port to open and close respectively said valve port as said cup-shaped valve member is moved away 5 from or toward said first-named member, whereby said cup-shaped valve member functions both as a main and a by-pass valve member controlling both said valve port and said by-pass.

WILLIAM B. MACKINTOSH. 10
